CLAIM

I claim the ornamental design for a front bumper guard, as shown and described.

DESCRIPTION

FIG. 1 is a perspective view of the front bumper guard; FIG. 2 is a front plan view thereof; FIG. 3 is a rear plan view thereof; FIG. 4 is a top plan view thereof; FIG. 5 is a bottom plan view thereof; FIG. 6 is a left plan view thereof; FIG. 7 is a right plan view thereof; and, FIG. 8 is a front view showing the front bumper guard with environmental features. Broken lines in FIG. 8 are for environmental purposes only and form no part of the claimed design.
